United States Patent

Des. 241,493
Patented Sept. 21, 1976

241,493

MODULAR FLOOR MAT

Ralph Ettlinger, Jr., Glencoe, and Glenn L. Beall, Gurnee,
Ill., assignors to Economics Laboratory, Inc., St. Paul,
Minn.

Filed Dec. 12, 1974, Ser. No. 531,891

Term of patent 14 years

Int. Cl. D6—11

U.S. Cl. D6—209

FIG. 1

FIG. 2

FIG. 1 is a perspective view of a modular floor mat showing our new design;

FIG. 2 is an enlarged scale bottom plan view;

FIG. 3 is a further enlarged scale right side elevational view, the front elevational view being a mirror image thereof; and

FIG. 4 is a similarly scaled rear elevational view, the left side elevational view being a mirror image thereof.

We claim:

The ornamental design for a modular floor mat, as shown and described.
